UNITED STATES PATENT OFFICE.

JOHN M. NEWTON, OF NORWICH, CONNECTICUT.

SHUTTLE-PLANER.

SPECIFICATION forming part of Letters Patent No. 412,930, dated October 15, 1889.

Application filed May 27, 1889. Serial No. 312,252. (No model.)

To all whom it may concern:

Be it known that I, JOHN M. NEWTON, a citizen of the United States, residing at Norwich, in the county of New London and State 5 of Connecticut, have invented a certain new and useful Improvement in Shuttle-Planers, which improvement is fully set forth and described in the following specification, reference being had to the accompanying sheet of 10 drawings, in which—

Figure 1 is a side elevation of a planer embodying my said invention, the bed-section being partly cut away to expose a shuttle held therein. Fig. 2 is a cross-section of a 15 similar bed, considerably enlarged, taken on line xx .

This invention is in that class of shuttle-planers in which the shuttle is held on centers, one of which is usually a strong thumb-screw, the side of said shuttle being trued up 20 by means of a finely-adjusted plane that slides on said bed, as on ways.

The particular purpose of this present invention is to provide, in connection with such 25 a shuttle-planer, simple and inexpensive devices by means of which a shuttle may not only be squared up, but may as readily be tapered or beveled, if desired. Many of the shuttles used in weaving are so beveled 30 to overcome, in a measure, the tendency and liability to jump upward and out of the shuttle-race as they shoot ahead. The slight bevel thus provided leaves the bottom of the shuttle a little wider than the top, thus 35 enabling the shuttle-box brake-spring to hold said shuttle down in the race as said shuttle passes under said spring.

In truing up a pair or set of shuttles for use in the same loom it is desirable that they 40 be exactly the same size, weight, and bevel, so that when a full shuttle is substituted for an empty one there will be no appreciable difference in the tension and texture of the woven fabric. The device which I have provided, 45 and which I will proceed to describe, when once adjusted enables the operator to true up and bevel a multiple of shuttles, so that they are all practically alike.

Referring to the drawings, the letter a in- 50 dicates the bed of my shuttle-planer, having feet or standards b , and having its upper

side planed up to form ways on and between which a plane c may travel. Said plane is supported on each side by bars d , that are attached to the main frame or shoe of the 55 plane by links e . The bars d are joined at one end to a cross-head f , that is slotted vertically, and in the slot thus provided is a thumb-screw h , whose inner threaded end is tapped into a rigid portion of the plane. 60 When said thumb-screw is rotated, the bars d are moved endwise, (substantially like one member of a parallel ruler,) and as a result the plane rises and lowers between the ways of the bed, according to the direction of 65 rotation of screw h . By this adjustment of the plane the depth of cut may be controlled.

At one or both ends, if desired, of bed a is a strong thumb-screw i , whose inner end is cupped to support one end of the shuttle. 70 The opposite end of said shuttle may be held in a cup-center formed in the bed, as shown in Fig. 1. To hold the shuttle against rotation on its centers, a thumb-screw k , having a loose washer on its inner end, is tapped into 75 bed a on one side, preferably about midway of its length. The clamping devices thus provided are sufficient to hold the shuttle rigidly in position while being squared up. When it is desired to bevel the side of a shuttle, other devices are added, as follows: A bar m is secured to the under side of bed a by bolts or screws m' , one of which may consist of a thumb-screw, as shown in Fig. 2, and for a purpose hereinafter explained. After a 80 shuttle n has been secured between the described centers, a wedge o is forced between the bar m and the lower face of the shuttle. This wedge may be tapered transversely as well as longitudinally, and when forced home 85 rocks the shuttle on its centers, throwing the upper face of the shuttle, which is to engage the cutting-bit, slightly out of a horizontal plane. The same result may be attained by means of a wedge of ordinary shape—that is 90 to say, one tapered only in its length—by unscrewing the thumb-screw m' and allowing one end of the bar m to drop slightly away from the bed.

The wedge o , when forced into place, not 95 only serves to adjust the shuttle to produce a bevel cut, but also provides a solid backing

at or about the center of the shuttle to prevent it from springing during the act of planing.

Having thus described my invention, I claim—

1. In a shuttle-planer, in combination with a bed having centers, as set forth, for supporting a shuttle, a cross-bar secured to the under side of said bed, and a wedge inserted between said bar and the shuttle, substantially as and for the purpose specified.

2. A bed having centers, as set forth, for supporting a shuttle, and a cross-bar attached to the under side of said bed and having one end vertically adjustable, as described, in combination with a wedge inserted between the said cross-bar and shuttle, substantially as and for the purpose specified.

JOHN M. NEWTON.
